TRACER CONTROLLED FEED
MECHANISM

Charles K. Salisbury, Waterloo, Iowa

Application February 23, 1937, Serial No. 127,098

17 Claims. (Cl. 82—14)

My invention relates to tracer controlled feed mechanism and is an improvement on my pending application, Serial No. 101,095, filed Sept. 16, 1936, Compound feed control mechanism.

The objects of my invention are: to provide greater accuracy of finished parts by eliminating unnecessary reversing of the feed screws from hunting, to reduce the effect of back-lash on the feeding movements, to provide a single magnetic clutch for the automatic operation of a feed screw in both directions, to provide means to reverse the rotation of said clutch by action of the tracer, to provide means whereby the operation of associated feed screws are dependent on each other to prevent unnecessary reversing of feed direction, to provide a tracer adapted to automatically move on three sides of a rectangle, to provide means cooperating with a pattern to control a driving connection with the cross feed screw independent of the tracer, to simplify boring and turning operations, and to provide means to automatically control the feed of the carriage by means of the splined shaft.

With the above and other objects in view, my invention comprises the herein described tracer controlled feed mechanism and all equivalents.

Figure 1 is a plan view of a lathe equipped with the mechanism herein described.

Figure 2 is an end view of the mechanism shown in Figure 1.

Figure 3 is a broken section taken on line 3—3 of Figure 1, showing the cross feed screw take-up.

Figure 4 is a plan view of the tracer unit with the cover removed.

Figure 5 is a side view of the tracer unit with the cover in position and partially broken away.

Figure 6 is a sectional view of the tracer unit taken on lines 6—6 of Figure 4 with the protective cover removed.

Figure 7 is a sectional view of the tracer unit taken on lines 7—7 of Figure 4.

Figure 8 is a sectional view of the tracer unit taken on lines 8—8 of Figure 4 but with the protective cover in position.

Figure 9 is a plan view of one of the magnetic clutch and brake units sectioned on lines 9—9 of Figure 10.

Figure 10 is an end view of the mechanism shown in Figure 9.

Figure 11 is a side view of the clutch and brake mechanism shown in Figures 9 and 10.

Figure 12 is an end view of a portion of the

outer clutch plate showing a driving projection and with release spring.

Figure 13 is a top view of the mechanism shown in Figure 12.

Figure 14 is an inverted plan view of the motor 5 reversing switches and controlling mechanism.

Figure 15 is an inverted side view of the mechanism shown in Figure 14.

Figure 16 is a sectional view of the mechanism shown in Figure 14 taken on line 16—16 10 of Figure 14.

Figure 17 is a partial sectional view of the latch plate and the speed limit switches taken on line 17—17 of Figure 14.

Figure 18 is a plan view showing the cross feed 15 screw release in its hookup position.

Figure 19 is a diagrammatic showing of the electrical connections.

Figure 20 is a partial sectional view of the speed cut-out switch mechanism taken on line 20 20—20 of Figure 14.

Figure 21 is a diagrammatic showing of tracer operation.

Figure 22 shows setting of tracer unit for face-plate work. 25

Figure 23 shows a modification of tool setting and a discontinuous pattern.

Figure 24 is a modification using double tool setting.

Fig. 25 is a modification showing special tool 30 setting.

Figure 26 is a sectional view of a modified magnetic clutch showing an air gap in the magnetic circuit.

A lathe having a bed 50, Figures 1 and 2, is 35 provided with a rotating spindle 51 adapted to carry a work piece 52.

A carriage 53 slides on the bed and carries a cross slide 54 which is provided with a compound rest 56 on which is secured a cutting tool 55 to 40 operate on the work.

Two brackets 58 and 59, Figures 1 and 2, are secured at the rear of the lathe. The bracket 59 being broken away in Figure 2 to prevent obstruction of the view. 45

These brackets carry a support 60 which is provided with a base surface 61 and a vertical wall 62 accurately machined in planes parallel with the lathe center.

A pattern 63 engages the wall 62 for cross location and is secured to the support 60 by screws 64. 50

The carriage is moved in either direction by a lead screw 65 or by a splined shaft 66 as shown 55

- in Figures 1 and 2. The cross slide is moved in either direction by a cross feed screw 68.
- The cross feed screw is rotated in either direction by a single reversible magnetic clutch 70, Figures 1, 2, 9 and 10. The carriage is moved in either direction by rotation of either the lead screw or the splined shaft operated by a single reversible magnetic clutch 70a of identical construction and operation.
- 10 The magnetic clutch 70 is provided with a bearing shaft 74 secured in bearings 75 and 76 to a bracket 77. The body is provided with annular grooves 78 and 79 in which are placed the magnet windings 81 and 82 in series with each other and connected with insulated collector rings 83 and 84 which are contacted by carbon brushes 85 and 90 to maintain a circuit through the clutch windings.
- 15 A clutch disc 86 is provided with a shaft 87 secured in bearings 88 and 89 to the bracket 77 with its shaft in line with the shaft 74 to allow the disc to contact with the driving face 91 of the clutch and to rotate therewith when magnetism is applied.
- 20 25 An outer clutch ring 92 is carried by the clutch 70 by three driving brackets 93 secured thereto which engage with driving projections 94 on the outer ring as shown in Figures 9, 10, 12 and 13 to give positive drive of the ring with the clutch 30 but to permit of slight end movement. The clutch disc 86 is placed between the outer ring and the clutch face 91 and free to rotate when the magnetism is released. The disc 86 is very thin and is held between the clutch face and the 35 outer ring very strongly when the clutch is energized.
- Three small leaf springs 95, Figures 12 and 13, serve to hold the outer ring 92 in a direction away from the clutch face when the clutch mechanism is released.
- 40 45 The clutch windings 81 and 82 are held in position by non-magnetic plates 112. The shaft 87 is provided with a brake disc 96 which rotates therewith, Figures 9, 10 and 11. A slight end movement of the shaft permits of engagement of a face of the brake disc with a fixed brake member 97 by means of a swinging brake lever 99 pivoted at 101 to a boss 102 secured to a bracket 77 and actuated by a brake spring 103 to force a quick stop of the disc 86 and parts controlled thereby when the clutch circuit is broken.
- 50 55 When the clutch circuit is energized, coils 105 and 106 supported by a plate 104 secured to the bracket 77 and in series with the clutch windings 81 and 82, act to attract an armature 107 of the brake lever 99 and release the brake. The fixed brake member 97 is adjustably secured to the bearing 88 by means of adjusting screws 108 and 109.
- 60 65 The clutch body 70, the disc 86 and the outer clutch ring 92 should all be of soft steel adapted for quick magnetic changes to increase the speed of clutch action.
- 65 70 The clutch and the brake discs as well as all parts carried by the shaft 87 are made as light as possible to permit of high rotative speed and quick stopping.
- 70 75 A condenser 113 is placed across the clutch and brake coil leads to increase the speed of demagnetizing.
- 75 As a closed magnetic circuit does not respond readily to reduction of the magnetizing current, a slight air-gap 115 may be maintained in the special clutch body 72 between the clutch face 91 and the disc 86 as shown in the modification shown in Figure 26.
- The bracket 77 is solidly bolted to the rear of the carriage 53 and moves therewith. On its lower surface is secured an electric motor 116 provided with a gear wheel 118 meshing with an idle gear wheel 119 supported by the bracket. The idle wheel meshes with a gear wheel 121 secured to the outer end of the clutch shaft 74 to rotate the clutch body 70 in the direction determined by the rotation of the motor.
- The clutch shaft 87 carries a small pinion 122 and a larger pinion 123 rotating therewith.
- A shaft 125, Figures 1 and 2, having bearings 126 supported by the bracket 77, carries a gear 127 set consisting of a gear 127 which may mesh with the pinion 122 and a gear 128 which may mesh with the pinion 123 by sliding on a spline on the shaft to provide a variable gear reduction. Any other gear change mechanism may be substituted.
- The shaft 125 carries a gear 131 adapted to mesh with a gear 132 carried at the rear end of the cross feed screw. By pushing a control rod 134 supported on the lathe carriage by clips 135, Figures 1 and 2, a lever 136 connected thereto by a link 138 and pivoted to the bracket at 139, Figure 18, is swung to the latched position shown in Figure 18. The gear 131 is thus moved on its driving spline 141 against a spring 142 by means of a forked collar 143 pivoted at 145 to the lever 136 to disconnect the gear 131 from its drive of the cross feed screw gear 132. The gears are held out of mesh by a projection 147 on the lower arm 140 on the lever 136 engaging with a projection 148 on an armature lever 151. This lever is pivoted at 152 to a support 153 secured to the bracket 77 and is retained in latching position by a spring 154.
- A magnet 156 serves to unlatch the lever 136 when it is energized and permit the spring 142 to force driving engagement of the gears.
- To permit of greater ease of engagement of the gears 131 and 132, the engaging ends of the teeth in both gears are cut on an angle as shown at 157 in Figure 18. This permits of positive engagement although the cross slide is being rapidly moved by the operator.
- A tracer, Figures 1 and 2, and detailed in Figures 4, 5, 6, 7 and 8, consists of a base 161, side walls 162, a top plate 163 and a removable protective cover 164.
- A primary lever 166 is secured by pivot points 167 between the top plate 163 and the base 161 for movement in a single plane. A secondary lever 171 is secured to side projections 173 of the primary lever by pivot points 174 to also swing in a single plane. A removable tracer point 175, provided with a stem 176 which is inserted in a hole 177 bored in the secondary lever (Figure 5) is clamped in position by a taper threaded nut 178.
- The center of the tracer point 175 is placed at an angle of about 45 degrees relative to the pivot point of the primary lever 166 when moving in the direction of the one-way feed setting of the tracer indicated by an arrow 179 in Figure 4. This angle is indicated at 181 in Figure 4. It is also placed at an angle relative to the pivot point of the primary to the secondary lever as indicated at 183 of Figure 4.
- The primary lever 166 carries a stiff safety spring lever 184 and also a rigid arm 186, both insulated from the primary lever and from each other as shown in Figures 4 and 5. They are 75

provided with contact points 188 normally in contact to carry the line current for operation of the clutches 70 and 70a. These contacts open upon excessive deflection of the tracer point and stop the feed in all directions.

The secondary lever 171 carries a contact arm 189 which is insulated therefrom and carries three electrically connected points 191, 192 and 193. It also carries a plate 195 secured thereto but insulated therefrom by an insulating plate 199, as shown in Figures 4 and 6. This plate has three connected contact points 196, 197 and 198.

A spring 200, Figures 4, 7 and 8, tends to independently hold both primary and secondary levers and the parts fixed thereto in their full line positions shown in Figure 4. An insulated screw 201 limits the movement of the secondary lever and the arm 189 in the opposite direction by its point contacting with the lever 189.

A yoke 203, Figures 4 and 5, is secured to but insulated from the end of the safety spring lever 184 and acts to limit the movement of the contact arm 189 away from it but permits of free movement of the contact arm in the opposite direction. An insulated set screw 205 limits the movement of the lever 186 due to action of the spring 200.

The contact points 191, 192, and 193 carried by the contact lever 189 make electrical contact with contact levers 207, 208 and 209 in the order given, while the contact points 196, 197 and 198 contact with contact levers 211, 212 and 213 in the order named.

The contact levers are all alike and each is pivoted at a point 215 to their base plate 216 which is insulated from the tracer base 161 but secured thereto.

A spring 217 permits flexible contact movement 40 of the contact lever which movement is limited by an adjustable stop screw 219.

The tracer carries the electric control for the clutch gear magnet coil 156. It consists of a contact lever stem 221 with its disc 222 which is seated in a recess in a bracket 223 secured to the side wall 162 of the tracer. A lever 224 swings on a pin 225 secured to the tracer side wall and has one end in contact with the disc 222. A spring 227 serves to maintain pressure against the disc to force the stem 221 to an upright position but deflectable in all directions. When so deflected an insulated contact point 228, Figures 4, 5 and 8 is forced against a contact point 229 of a lever 231 to close the circuit through the magnet coil 156. The lever 231 also swings on the pin 225 and is held against a stop 232 by means of a spring 234 to permit of excess deflection of the stem 221.

The tracer also carries a swinging contact lever 236 adapted to swing with a bearing pin 237 secured in bearings in the base 161 and the top plate 163. The lever 236 carries an insulated point 238 which is normally held by a spring 239 in contact with an insulated contact point 241 carried by the side wall.

The contact lever 236 cuts out the tracer contacts 196, 197 and 198 when using discontinuous patterns.

A plate 243 is secured to the base 161 of the tracer by means of rivets 244 and serves as a cover to an insulating plate 245 which acts as a bottom insulating support for four binding nuts 246, 247, 248 and 249 insulated from the base 161.

The binding nuts 246 and 247 are connected 75 to the spring 184 and to the arm 186 of the clutch

power circuit while the nuts 248 and 249 connect with the points 238 and 241 for power operation of the coil 156.

The plate 245 also carries five contact springs 251, 252, 253, 254 and 255 which are all insulated from the base and serve to complete the battery circuits controlled by the tracer.

A rigid arm 257, Figures 1 and 2, is adjustably secured to the cross slide of the lathe by bolts 258 and 261. At the rear end of this arm an insulating circular base plate 263 is secured by rivets 264 and carries three sets of contact points 1, 2, 3, 4 and 5, Figures 4, 5, 7 and 8, adapted to make contact with the clutch and motor controls and the tracer when the tracer is set in any one of the three operating positions.

A bolt 265 secured to the plate 243, Figures 5 and 7, directly below the center of the tracer point 175 and extending through the center of the circular base plate 263 and end of the arm 257, serves as a pivot on which the tracer is rotated for its various settings. A winged nut 266 serves to secure the tracer in the desired position.

The motor 116 for driving the cross feed screw 25 magnetic clutch 70 is identical in its construction and its control with a motor 116a used in driving the magnetic clutch 70a and is here shown as an alternating current motor provided with starting coils 270, Figure 19, for controlling the 30 direction of rotation of the motor and its associated clutch.

The motor is provided with an extended bearing shaft 271 which carries a brake disc 272 and a shifting screw 273 which rotate therewith as 35 shown in detail in the inverted Figures 14, 15 and 16.

A secondary shifter and brake plate 274 of nonmagnetic metal and carrying brake coils 275 and 276 is also supported by a bearing 277 on the 40 motor shaft 271 between the brake disc and the shifting screw and is held in neutral position by two springs 278 fixed thereto and having their opposite end secured to a fixed plate 279. Stops 281 and 282, fixed to the lower side of the bracket 45 77 and provided with cushions 280, limit the deflection from neutral in either direction and serve to prevent undue rotation when serving as a brake.

A shifter arm 285, Figures 14, 15 and 16 is pivoted to one end of an armature lever 287 which is supported by a bearing column 288 secured to the bracket 77.

The armature lever 287 is held against a stop 291 by a spring 292 to hold a contact end 293 55 of the shifter arm 285 out of contact with the shifter screw when inoperative. A lever 298, Figures 14, 15 and 16 is pivoted at 296 to a column 297 secured to the bracket 77. The lever is provided with shifting projections 301 and 302 60 against which the shifter arm contacts during shifting operations.

Light tension springs 306, having one end attached to a pin 308 on the arm 285 and the other end secured to projections 311 of the lever 298 65 serve to hold the arm in midshifted position when its point 293 is disengaged from the shifting screw 273. The shifting screw 273 and associated parts act as a time-delay mechanism.

A slot on the lever 298 engages with a pin 317 70 secured in an arm 318 of a switch lever 319 which is pivoted to a bracket 321 secured to an insulating side plate 322. A stop plate 320 limits the movement of the levers 298 and 319 in either direction.

A primary switch composed of blades 324 and 325, insulated from each other but held together by an insulating block 326, Figures 14, 15 and 19, are pivoted to brackets 327 and 328 which are insulated from each other by the side plate 322 on which they are secured. The brackets 327 and 328 as well as the brackets 363 and 364 are positioned relative to their connected parts as shown in the Figure 19. These switch blades are thrown 10 by a spring 331 secured one end to the block 326 and at the other end to an arm 332 of the switch lever 319 and are adapted to swing freely between the switch blades.

The brake plate 274 is provided with an arm 15 having its end bent at right angles to form an operating point 335 as shown in Figures 14, 15, 16 and 17. This point engages with a pin 336 secured to a latch plate 337 during the shifting of the secondary switch in either direction. The 20 latch plate is pivoted at 338 to one end of a lever 341 and is provided with two pins 342 and 343 which engage with a plate 344 secured to the bracket 77. A light spring 346 is secured at one end to a pin 347 of the lever 341 and at its other 25 end to an arm 348 of the latch plate to bring it to its operating position after deflection.

The lever 341 is pivoted at 351 to the bracket 77 and at its opposite end is hinged to a connecting link 352 which is hinged to an arm 354 30 of the secondary switch lever 356, Figure 15, which is of the same construction as the primary switch lever 319, previously described.

The switch lever 356 is pivoted to a bracket 358 secured to the side plate 322.

35 The secondary switch is composed of two short blades 360 and 361, Figure 19, pivoted to brackets 362 and 363, Figures 14, 15 and 19, which are insulated from each other by the side plate 322 on which they are mounted. The blade 360 has an 40 extended end 364 secured thereto but insulated therefrom by an insulating block 365, while the blade 361 carries an extension 366 also insulated from it by the block 365. This divides the secondary switch into four separate parts, insulated 45 from each other but moving together.

The secondary switch is thrown by a spring 367 secured to the block 365 and to the switch lever 50 356 in the same manner as described for the primary switch.

55 The side plate 322 carries a series of spring contacts 368 for the control of the various circuits when the motor 116 is operating in the direction of an arrow 424, Figure 16. A second insulating side plate 372 carries the contact springs 373 for the control of the various circuits when the motor 55 is rotating in the opposite direction.

A motor bushing 382, Figures 15 and 20, is reduced in diameter at its outer end to form a 60 stationary bearing support for a friction flanged sleeve 383 on which it may freely rotate. A second friction disc 387 is forced onto the sleeve with a comparatively thin friction plate 388 carried on the sleeve between them. This plate 388 is warped to frictionally bind it between the plates and tends to rotate with it to the extent permitted by a pin 384 engaging in a slot in a rocker lever 391 which is pivoted to brackets 392 secured to an insulating base 393. The rocker lever is 70 provided with a lateral arm 394 on either side of its pivot point which may engage with the free end of contact springs 395 and 396 secured at their outer end to the base 393. The spring 395 carries a contact point adapted to contact with a 75 point carried on a contact plate 397, Figure 20,

while the contact spring 396 likewise contacts with a contact plate 398.

A spring 399 serves to maintain the plate 398 and the rocker lever in neutral position.

The sleeve 383 is provided with a driving projection 401, Figures 16 and 20, against which a point 403 of either lever 405 or 406 may be moved by a spring 407 when the rotative speed of the motor has sufficiently dropped. These levers are pivoted at 408 to the rear face of the brake disc 10 272 and are limited by pins 411 against excessive movement.

The magnetic clutches 70a and 70 are driven by their reversible motors 116a and 116 which operate on 110 volt circuits.

An 8 to 10 volt battery 445 furnishes the current for the operation of the coils 426, 431 and 421a controlled by the tracer.

The carriage is driven by identical gear as used for operation of the cross slide. A gear 437 on 20 the shaft 425a may slide into driving mesh with a gear 438 on an extension of the splined shaft 66 or it may slide into mesh with a gear 440 on the lead screw 65.

The usual manual controls 447 and 448 move 25 the carriage and cross slide, while the usual split nut 449 operates the lead screw and a nut 451 controls the carriage movement by operating the regular friction clutch to connect the splined shaft to the transmission gearing in the carriage apron. 30

Operation in longitudinal turning and boring: The tracer base 161 is set in the position shown in Figures 1, 2, 23, 24 and 25. The carriage is moved in the direction of the arrow 30, Figure 1, by one-way control of the clutch 70a. The cross slide is operated in either direction by the clutch 70. The carriage is preferably driven by the splined shaft which is released at the nut 451 and the gear 131 is released by the control rod 134. The contact lever 221 carried by the tracer, is moved against the edge of support 60 at its starting point 444, Figure 1, by the manual controls. This energizes the coil 156 to instantly connect the cross feed screw for automatic control by the tracer.

45 The splined shaft 66 is connected by the nut 451 and both motors 116 and 116a are now started. It is merely necessary that the motor 116a be operating in the right direction for the proper feeding direction of the carriage.

The motor 116 has been rotating in the direction indicated by the arrows 422 of Figure 19 and in the direction opposite to the arrow 424 of Figure 16 and its direction of rotation will now be reversed to move the tracer point 175 toward the pattern 63. The tracer point is very close to the pattern but still out of contact and the contact arm 189 is held in the full line position shown in Figure 4 by the spring 200. In this position, the plate 195 on the arm contacts with the contact lever 213 and the line circuit through the clutch 70a is broken and the carriage remains stationary. (Contact is also made with the lever 212 which also controls the clutch 70a through the coil 421a as before but it is now disconnected and its action will be described later.)

55 The plate 195 of the arm 189 also contacts with the contact lever 211 which is now in circuit with the shifter coil 426. This operates to move the point 293 of the lever 285 into contact with the 70 teeth of the shifter screw 273, the rotation of which moves the side of the lever into contact with the projection 301, Figure 14, of the lever 288 and held there until the continued movement of the point 293 throws the primary switch to the

position shown in Figures 14 and 15. (Contact of the point 293 with the shifter screw may be only momentary and will be described later.)

The connections are now as shown in the diagrammatic Figure 19, with the connection from the motor winding 428 and the starting winding 270 to the line broken and the brake coil 276 connected.

When the brake coil 276 is energized, the ends 10 of its core 390, which also extends through the coil 275, are held very strongly to the brake disc 272 and the brake plate is rotated against the pressure of the springs 278 until contact of the point 335 of the brake plate with the stop 281. 15 The motor speed, due to inertia, is quickly reduced to near the stopping point and the point 603 of the centrifugal lever 406 engages with the projection 401 of the flanged sleeve 383 to frictionally move the friction plate 388 and the rocker lever 381 sidewise as shown by dot and dash lines of Figure 20 but in the opposite direction to that shown as the motor is rotating in the opposite direction. The contact between the spring 395 and the contact plate 397, in series 20 with the coil 276, is thus broken and the brake released. The springs 278 then act to bring the brake plate to its neutral position as shown in Figure 16 and throw the secondary switch by moving the latch plate and connected parts by 25 contact of the point 335 and the pin 336. The switch then takes the position shown in Figures 14 and 15, the circuit through the brake coil 276 is opened, the motor winding 428 is connected to the line as is the starting winding 270 with reversed connections. At the same time, the shifter coil 426 and the operating coil are reversed in their connection with the contact levers 207 and 211 and the contact levers 212 and 209 are shifted into control of the coil 421a operating the clutch 40 70a instead of the former contacts 213 and 208.

As the tracer arm 189 is maintained at its previous position, contact of the plate 195 and the contact lever 211 acts to energize the clutch 78 through its coil 431 and the tracer point is 45 moved into contact with the pattern. The movement is continued until the arm 189 breaks the contact between the plate 195 and the contact lever 211 and the arm 189 is brought to about the position shown by dot and dash lines of Figure 4 50 and the cross feed stopped. The primary lever of the tracer is not deflected by this contact but maintains its full line position or as shown in the position 452 in the diagrammatic Figure 21.

In the mean while, the contact between the 55 plate 195 and the contact lever 212 has been broken and the carriage is moving in the direction of the arrow 30 of Figure 1, to bring the tracer point into contact with the point 446, Figure 1, at the center line 453 of the pattern. Continued 60 movement then swings both primary and secondary levers of the tracer to the position shown at 454 in Figure 21, due to the angular relation of the tracer point and the pivoted point of the primary lever.

65 When the tracer arm is swung to this position, contact is first made between the arm 189 and the contact lever 207 which is now connected to the shifter coil 425. Continued movement of the carriage still further moves the arm 189 until 70 contact is established with the contact lever 209 and the movement of the carriage stopped.

The motor is now ready for reversal in direction of rotation which is done in the same order as before described with reversed movements of 75 the operating parts.

Before the brake plate 274 can swing in the opposite direction in reversing it is necessary that the latch plate swing back to its operating position as shown in Figure 14 after being deflected to the position shown in Figure 17. This is done when the point 335 of the brake plate has moved close enough to its stop, on either side, to clear the pin 336.

Upon reversal of the motor, the feed of the cross slide will be in the direction of the arrow 10 31 of Figure 1 and the carriage will operate to the extent required to maintain tracer contact with the pattern. This will continue until a point 458 on the pattern is reached by the tracer point, when reversing will again take place. The 15 motor is again reversed when a point 459 is reached but will then continue until the operation is completed. The tracer then continues to move along the pattern until a point 460 is 20 reached where no further movement is possible because of one-way operation of the carriage. The feed in one direction, or the other, will still persist until the contacts 188 of Figure 4 are 25 opened by the excess movement of the tracer point and the clutches 70 and 70a are rendered inoperative.

When the tracer is moving over the edge of the pattern at 457, Figure 1, it is desired that there be no reversal of the motor due to very slight inequalities in the pattern which might cause 30 such action. To prevent reversing, a plate 462, Figures 1, 2, 5 and 7, is secured to the bottom of the pattern 63 in position to contact the lever 236 carried by the tracer, to open the contacts 238 and 241, Figure 4, and disconnect the plate 35 195 from the battery circuit. This renders the tracer arm 189 inoperative in the direction controlled by the plate 195 but operative in the opposite direction.

This same action takes place where discontinuous patterns are used as in the modification 40 Figure 23.

Many times it is desirable to provide a starting point on a pattern where the lever 224 cannot contact with the edge of the support 60. In 45 such cases a starting plate 463 Figures 5, 7, 22, 23, 24 and 25, is secured to the under side of the pattern to make contact for energizing the coil 156.

The starting plate may be used as a stop at 50 other than the regular starting points if desired.

When a second cut over the surface previously machined is desired, the carriage and cross feeds are released in the manner previously described and the tracer again manually returned to the 55 starting point 444. The tracer point 175 is then raised to permit of its reduced stem 176 to contact with the pattern as is common in such work. The second cut is then performed as previously described.

The advantage of the cut always being taken in the same direction is that the cutting tool may be formed to much greater advantage, resulting in both better and faster work. To do this, in previous constructions, required great care to prevent damage to the tracer when manually moving 65 it to the starting point.

In boring the form shown in Figure 25, modified tool action is used. The special cutting tool 464 is turned upside down and is placed to operate on the work 465 at the rear of the center line of the lathe as required in lathes which are not adapted for machine operation in the reverse direction. The specially formed tracer point 467 follows the pattern 466 in the manner and in the 75 70 75

direction previously described for cylindrical turning.

In boring the core box 469, Figure 23, modified tool setting is also used. The lever 221 is manually moved against the starting plate 463 and the special tracer point 473 moves along the face 477 until contact is made with a swinging stop plate 475 which stops the progress until comparative measurements, relative to the work and the cutting tool 472, are made. The stop plate is then swung to its dot and dash position 476 and the tracer progresses along the pattern until reaching the point 478 when the contact lever 236 contacts a lengthened plate 479, which is equivalent in action to the plate 462, previously described. The bore is then formed cylindrical, without movement of the cross slide, until the tracer point contacts the opposite adjustable end plate 482. The work is, from this point, formed according to the pattern and the tracer is stopped and the circuit of both clutches opened by the angled stop plate 483.

In Figure 24 the inverted boring tool 485, indicated by full line, operates on the work 486 under control of the tracer point 473 moving over that portion of the pattern 487 as indicated at 488. The regular boring tool 489, shown by dot and dash lines, operates under control of the same tracer, shown by dot and dash, when moving over that portion of the pattern indicated at 491. The tracer point starts in both cases at its starting point 493 and 494 and moves in the same direction.

The advantage of using this method over the face plate method of machining the same part, as shown in Figure 22, is that square corners may be cut at the points 495. In practically all pattern work, such corners are required. The tool action is also very much better.

A very material advantage of using the modified tool operations shown in Figures 23, 24 and 25, is that one-way operation of the carriage is required, only, even for complicated work and the templets and tracer are then used as in turning.

In normal tracer action, where no motor reversal is required, the arm 189 will vibrate between the contact levers 211 and 207 connected to the operating coil 431 and the shifter coil 426, and contact both of them if the contacts be set close and a fast feed be used. The contact point 293 of the shifter arm 285 will then engage the shifter screw 273, but no motor reversal will result as it is again withdrawn before contact with the lever 298 and the point 293 returned to its mid-shifted position by the springs 306.

The vibration of the tracer arm 189 may also alternately contact the levers 208 and 212 resulting in improper operation of the clutch 70a. To prevent this, the contacts 213 and 208 are cross-connected, as are the contacts 212 and 209. The tracer arm must move much farther to contact the contacts 213 and 209 than in contacting 212 and 208. The switch blade 464 connects the proper set for either direction of rotation so that the arm moves much farther for operative contact on the shifting side than on the operating side.

For maximum tracer efficiency, the contact levers 207 and 211 should be set to permit the tracer arm 189 to move only slightly from its central un-contacted position to contact either. The contact 212 should be set to require the arm to move from its central position, double the distance required to contact the lever 211, and also double the distance to contact 208 as required to

contact 207. The levers 213 and 209 require much greater movement for contact than 212 and 208.

It will again be noted that the clutch 70 is energized only upon contact of the tracer arm with contact lever 211 or 207. The clutch 70a is energized only when there is no contact of the tracer arm with the contact levers 212 and 209 or with 208 and 213.

The advantage of requiring a greater period of time after contact before operation, and also a greater movement of the tracer arm on the side not operating, before contact, is that hunting action of the tracer and the clutches, is eliminated.

The effect of back-lash in the mechanism between the clutch and its screw is entirely eliminated, also, as the movement is always in the same direction.

In those mechanisms using two tracer controlled clutches or like mechanism for reverse operation, unrestricted tracer control very much slows up the effective operation if back-lash be present as this must be overcome in both directions by the cross slide upon an overthrow of the tracer arm. The work is thus roughened.

The tracer operates with a setting as shown in Figure 4, moving in the direction of the arrow 179 for one-way control of the clutch 70a and moving in both the same and the opposite direction of the arrow 497 for control of the clutch 70.

The action of the tracer is diagrammatically shown in Figure 21, when operating at right angles on three sides of a rectangle. With the tracer setting as just described, the tracer arm 189 is moved by contact with the yoke 203, carried by the primary lever, when moving in the direction of the arrow 501 and both primary and secondary levers move together for control operation. When the tracer is moving in the direction of the arrow 502, the tracer arm 189 alone moves for control operation as the primary lever is deflected by the spring 200. When the tracer is moving in the direction of the arrow 503, both tracer arm and primary lever are deflected by the spring until the angled face 504 is reached. The tracer arm 189 alone is then deflected to control the operation of the clutches 70a and 70.

The addition of the second lever to the tracer alone allows it to control when contacting the angled face 504 or other similar contact surfaces.

The clutches 70 and 70a must respond very quickly to the tracer action and must magnetize and de-magnetize very quickly.

The outer clutch plate 92 much reduces the magnetizing effort required for the same effective drive and the clutch disc 86 is much reduced in weight, allowing higher clutch speed.

By placing the clutch disc brake releasing magnets 105 and 106 in series with the clutch windings 81 and 82, the brake is applied and released much quicker upon clutch action than when using a previously used magnetic brake which is electrically operated for brake application after the clutch circuit is broken.

The magnet coils 105 and 106 may also be placed in parallel, instead of in series, with the clutch windings (not shown).

To simplify the wiring diagram, the motor 116a and its clutch 70a are understood to have a battery and operating coils that duplicate those shown in Figure 19, as well as its own controlling switches.

The contact springs 251, 252, 253, 254 and 255

on the insulating base plate 245 of the tracer, contact with the contacts 1, 2, 3, 4 and 5 on the base plate 263 in the order given when the tracer is set for longitudinal turning and boring, as shown in Figures 1, 2, 4, 5, 7, 8, 23, 24 and 25. These contacts connect the tracer elements to the battery circuits as shown in Figure 19.

When the tracer base 161 is swung to the position shown in Figure 22, the machine is properly connected for face-plate work. The one-way feed is in the direction of the arrow 31 of Figure 1 and the carriage feed is in either direction by either the splined shaft 66 or by the lead screw 65.

A second longitudinal boring position of the tracer (not shown but opposite in setting to that shown in Figures 1, 23, 24 and 25) may be used. It requires one-way movement of the carriage opposite to the arrow 30.

Back-lash should be eliminated as much as possible in the cross feed screw, as high tool pressures may cause the comparatively light cross slide to suddenly move to the full extent of the back-lash and cause roughened work. By placing a second nut 507, Figures 1 and 3, on the screw 25 in addition to its regular nut 508 which is secured to the slide 54 by a screw 509, and adjustably securing this second nut by clamping screw 511 after adjustment of the set screw 512 has moved the nuts 507 and 508 apart by contact with its conical end 513, the back-lash of the cross feed screw is reduced as desired.

The single automatically reversed clutch drive and requiring of greater time interval before operation in the reverse direction in response to tracer action, may be used independently or together in other mechanism than herein shown and I do not wish to be so limited. I claim the above described invention broadly and all equivalents.

40 I claim:

1. In combination, a pattern, a tracer adapted to traverse said pattern, means controlled by said tracer for relatively feeding said tracer in either direction at an angle to said traverse of tracer 45 and pattern, a projection carried by said pattern, and a contact piece moving with said tracer adapted to contact with said projection and prevent the feeding control operating in one direction but permitting it to operate in the other.

50 2. In a lathe, the combination of a cross slide, a screw for moving said cross slide in either direction, a tracer carried by said slide, means under control of the tracer to operate said screw, a fixed pattern adapted to operate said tracer when in 55 contact therewith, means to disconnect the tracer controlled means from the screw, a contact moving with said tracer and adapted to contact a projection fixed relative to said pattern, and means to re-establish operation of the screw by the 60 tracer controlled means when the tracer has been manually moved close to the pattern to bring the contact carried with the tracer into contact with said projection but before the tracer has contacted the pattern.

65 3. In a mechanism of the character described, the combination with a slide operated by power in one direction only and a second slide operated at an angle relative to the first slide by power in both directions, of a tracer comprising a lever pivoted to its support for movement in a single plane, a second lever pivoted to the first lever and movable in a single plane, a pattern engaging tracer point on said second lever, contacts in position to be closed by contact upon movement of the 70 tracer point to stop the movement of the first

slide, and contacts in position to be closed by contact when the tracer point is moved to operate the second slide in the desired direction, both of said tracer levers being moved for control when the tracer point is moved in some directions and the second lever alone moved when the tracer point is moved in other directions.

5 4. In the mechanism as claimed in claim 3, in which excess movement of the tracer point opens an electric circuit of the power means operating both slides to render them inoperative.

5 5. In a mechanism of the character described, the combination of a slide mounted for feeding movement, a clutch member operatively connected to move said slide and provided with a thin clutch disc, a power rotated clutch member provided with a driving surface moving adjacent to a face of the clutch disc, a ring disc carried by and rotating with the power clutch member adjacent to a face of the clutch disc opposite to its first said 20 face, and an electric magnetizing element cooperating with said power clutch member adapted when energized to magnetically bind it with the clutch disc and ring disc to move said slide.

6 6. In a lathe, the combination of a carriage 25 operated by a splined shaft, a cross slide mounted on said carriage and movable by a screw, a tracer cooperating with a pattern to control the movements of said carriage and cross slide, means to release the carriage from its drive by the splined shaft, means to release the screw of cross slide 30 from control by said tracer, and means whereby control of said screw by said tracer is automatically re-established before contact of the tracer with the pattern when manually moved toward 35 contact.

7 7. In a lathe, the combination of a carriage moved by power in a single direction, a cross slide carried by said carriage and movable by power in either direction, a tracer co-operating with a pattern to control the power for movements of said carriage and said cross slide, an inverted cutting tool carried by said cross slide to operate at the rear of the center of the lathe to bore work carried thereby, and means to operate said lathe 45 when boring with an inverted tool in the same manner as when turning with a tool as commonly used.

8. In a lathe, the combination of a carriage movable by power, a cross slide on said carriage 50 also movable by power, a tracer cooperating with a pattern to control the power for movements of said carriage and cross slide, a cutting tool adapted to operate on work carried by the lathe over that portion of its surface controlled by the 55 tracer in contact with a portion of said pattern, and a second cutting tool adapted to be inverted and operated back of the lathe center to operate on that surface of the work controlled by the tracer when contacting a second portion of said 60 pattern.

9. In a mechanism controlled by a pattern to produce work, the combination of a member mounted for relative feeding movement, a screw co-operating with said member for direct and 65 reverse feed, a magnetic clutch adapted to drive said screw in either direction and to control the feeding movements of said screw, a motor to drive said clutch, means controlled by the movement of said member to automatically operate 70 said clutch, and means controlled by the movement of said member to automatically reverse the direction of rotation of said motor.

10. In a mechanism controlled by a pattern to produce work, the combination of a member 75

mounted for relative feeding movement, a screw co-operating with said member for feeding movements in either direction, a magnetic clutch adapted to drive said screw and to control its feeding movements in either direction, means controlled by said member to automatically control said clutch for the feeding movements, and means controlled by the movement of said member to automatically reverse the direction of rotation of said clutch.

11. In a mechanism controlled by a pattern to produce work, the combination of a member mounted for relative feeding movement, a screw co-operating with said member for feeding movement in either direction, a magnetic clutch adapted to drive said screw and to control its feeding movements for both directions, means controlled by the movement of said member to automatically operate said clutch for the feeding movements, and means controlled by the movement of said member to automatically reverse the direction of feeding movement of said screw.

12. In a mechanism controlled by a pattern to produce work, the combination of a member mounted for relative feeding movement, a rotatable shaft co-operating with said member to feed it in either direction, a magnetic clutch adapted to drive said shaft and to control its feeding movements in both directions, means operated by the movement of said member to automatically operate said clutch for the control of the feeding movements, and means operated by the movement of said member to automatically reverse the direction of feeding movements of said shaft.

13. In a mechanism controlled by a pattern to produce work, the combination of a slide mounted for feeding movement, a clutch member comprising a thin disc operatively connected to the slide, a power rotated clutch member provided with a driving surface moving adjacent to a face of the disc, a ring member carried and driven by the power clutch member adjacent to a face of said disc opposite to its first said face, and an electric magnetizing element adapted to magnetically draw the ring member toward the power clutch member and bind the disc between them to move the slide when the magnetizing element is energized.

14. In a mechanism controlled by a pattern to produce work, the combination of a member mounted for feeding movement, a power mechanism to move the member toward and from a pattern, a tracer carried by the member and contacting with the pattern to control the power mechanism, a time-delay mechanism interposed between the tracer and the power mechanism to delay the response of power action to tracer control when the tracer is deflected into contact in the direction opposite to the feed direction as determined by the pattern but permit of immediate response in the opposite direction, and means controlled by the time-delay mechanism to alter its connections to the tracer when the

direction of feed has been changed by the form of the pattern.

15. In a mechanism controlled by a pattern to produce work, the combination of a member mounted for relative feeding movements, a power mechanism to move the member toward and from a pattern and also transversely thereof, a movable tracer carried by the member and contacting with the pattern to control the power mechanism and adapted to close a contact having connection for direct control of the power mechanism to move the member away from the pattern when the tracer is traversing those portions of the pattern that determine that the feed shall be in that direction, a second contact directly connected to stop the transverse movement of the member when closed by the tracer deflected in the direction to close the first said contact, a third contact adapted to be closed by the tracer to move the member toward the pattern, a time-delay mechanism interposed between the third contact and the power mechanism to delay its response to tracer action, a fourth contact adapted to be closed by the tracer when deflected to close the third contact and adapted to stop the transverse movement, means operated by the time-delay mechanism to render the fourth contact inoperative when the feed is from the pattern, and means under control of the time-delay mechanism to shift its control to the first and second said contacts and to directly connect the third and fourth contact to the power mechanism when the direction of feed is changed toward the pattern by change in pattern form.

16. In a mechanism controlled by a pattern to produce work, the combination of a member mounted for feeding movements, a power mechanism to move the member toward and from a pattern and also transversely thereof, a movable tracer carried by the member and contacting with the pattern to control the power mechanism, a contact adapted to be closed by the tracer when deflected by the pattern to move the member away from the pattern, and a second contact adapted to be closed to stop the transverse movement of the member after the closing of the first contact by increased deflection of the tracer which upon reverse movement acts to open the second contact while the first contact is closed to permit of simultaneous transverse feed and also away from the pattern.

17. In a mechanism controlled by a pattern to produce work, the combination of a member mounted for relative feeding movement, a rotatable shaft cooperating with said member for feeding movement in either direction, a clutch adapted to drive said shaft and to control its feeding movements for both directions, means controlled by the movements of said member to automatically operate said clutch for the feeding movements, and means under control of said member to automatically reverse the direction of feeding movements of said shaft.

CHARLES K. SALISBURY.
